UNITED STATES PATENT OFFICE

OLIVER GROSS, OF TOLEDO, OHIO, ASSIGNOR TO THE GROSS PHOTO SUPPLY COMPANY,
OF TOLEDO, OHIO, A CORPORATION OF OHIO

EASEL PHOTO HOLDER

Application filed March 11, 1929. Serial No. 345,948.

This invention relates to a frame adapted to rest upon a substantially level surface and to support a photograph or similar article in a suitable position for display.

The object of the invention is to provide a folder of this kind, made from cardboard or similar flexible material, which may be easily set up and in which the supported parts are interlocked and held in such relation as to constitute a well-braced and durable construction.

The specific construction of the invention, in its preferred embodiment, and the advantages thereof, will be more particularly explained in connection with the accompanying drawing, in which,

Figure 1 is a rear elevation of the invention set up.

Figure 2 is a perspective view of the folder partially folded.

Figure 3 is a side elevation of the folder as it appears in Figure 1.

Figure 4 is a horizontal section taken on line 4—4 of Figure 3.

The folder, which constitutes the subject-matter of my invention, comprises a front panel 5 on which a photograph or the like may be mounted. A bottom flap 6 is connected to the lower end of the panel 5 and an upper flap 7 is similarly connected to the upper end of the panel. The folder is made from cardboard or similar material, which is scored or creased along the lines 8 and 9, respectively, thus providing fold or hinge lines, about which the flaps may fold.

The upper flap 7 is also formed with fold lines or creases 10 and 11 which converge from the upper corners of the flap to a point 12 near the center thereof, and a similar fold line or crease 13 extends along the longitudinal center line of the flap from the point 12 to the end thereof, thus forming lateral leaves 14 and 15 which may be flexed about the lines 10, 13, and 11, 13, respectively. The double lines at 10, 11 and 13 represent narrow portions of the material which are crinkled to facilitate flexure on these lines. Thus, when the folder is set up the upper part of the flap 7, together with the leaves 14 and 15 form a trihedral

angle having its vertex at the point 12 and the lower end of the flap is L-shaped in cross-section, similar to an angle bar. The lower ends of the leaves 14 and 15 are formed with tabs 16 and 17, respectively, and the lower flap 6 is formed with obliquely disposed slits 18 and 19 to receive the tabs and thus form an interlocking connection between the flaps.

When the folder is set up in the manner described, the form of the flap 7 gives it a marked strength and rigidity, although the material of which it is made may be quite flexible. This strength and rigidity is due primarily to the angular relation of the different parts of the flap 7 and to the fact that the two flaps interlock in such a manner that each part is positively held in position. The folder may be very easily set up and will last indefinitely without any material distortion, yet may be easily taken down and laid flat, when desired.

While I have shown and specifically described only one embodiment of the invention, it is obvious that various modifications may be made therein, without departing materially from the essential features of the invention, or sacrificing any of its advantages. It is my intention, therefore, to include all such modifications within the scope of the appended claims.

What I claim is:

1. A device of the character described, comprising a panel adapted to be supported in inclined position, a flap connected to the upper edge of the panel by a fold line to constitute a prop, said flap having a central longitudinal fold line extending from its end part way of its length about which the flap may be flexed to stiffen the same longitudinally, a flap connected to the lower edge of the panel, and tabs formed at the end of one of said flaps, the other flap having slits arranged in angular relation in a position to receive said tabs to effect an interlocking engagement.

2. A device of the character described comprising a panel adapted to be supported in inclined position, a flap connected to the upper edge of the panel by a fold line to

constitute a prop, said flap having three fold lines extending in different directions and meeting near the center of the flap to form leaves, said leaves having tabs at the ends, and a flap connected to the lower end of the panel and having slits to receive said tabs, said slits being angularly disposed with relation to each other, so that when the tabs engage the same, said leaves are in different planes, thereby stiffening each other.

3. A device of the character described, comprising a panel adapted to be supported in inclined position, a flap connected to the upper edge of the panel by a fold line to constitute a prop, said flap having three fold lines extending in different directions and meeting near the center of the flap to form leaves flexibly connected, a flap connected to the lower edge of the panel and adapted to meet the first mentioned flap, and means for interlocking the meeting portions, said means including tabs upon one flap and slits in the other, so arranged that the first mentioned flap is held with its leaves forming an angle with each other, whereby one leaf stiffens the other.

4. A device of the character described, comprising a panel adapted to be supported in inclined position, a flap connected to the upper edge of the panel by a fold line to constitute a prop, said flap having fold lines extending from its upper corners and converging to an internal meeting point and a fold line extending from the bottom edge to said meeting point to form lateral leaves which may be rocked about the lines meeting at said point to form a trihedral angle, and means for securing the bottom edges of said leaves in spaced relation to the bottom edge of said panel.

5. A device of the character described, comprising a panel adapted to be supported in inclined position, a flap connected to the upper edge of the panel by a fold line to constitute a prop, said flap having fold lines extending from its upper corners and converging to an internal meeting point, and a fold line extending from the bottom edge to said meeting point to form lateral leaves which may be rocked about the lines meeting at said point to form a trihedral angle, tabs at the lower end of said flap, and a flap connected to the lower edge of the panel and having slits to receive said tabs, said slits being so arranged that the leaves will be held in their angular relation as long as the tabs are engaged with the slits.

In testimony whereof I have hereunto signed my name to this specification.

OLIVER GROSS.
